UNITED STATES PATENT OFFICE.

JOHN EDWARD GLOEKLER AND ALFRED B. STAHL, OF PITTSBURGH, PENNSYLVANIA.

STOVE-CANOPY.

1,174,851.

Specification of Letters Patent.

Patented Mar. 7, 1916.

Application filed May 13, 1915. Serial No. 27,861.

To all whom it may concern:

Be it known that we, JOHN EDWARD GLOEKLER and ALFRED B. STAHL, citizens of the United States, residing at Pittsburgh, in the county of Allegheny and State of Pennsylvania, have invented new and useful Improvements in Stove-Canopies, of which the following is a specification.

Our present invention relates to stove canopies; and it contemplates the provision of a canopy designed more especially for use in conjunction with the large ranges of hotels and restaurants, and constructed generally with a view of reducing the fire risk and at the same time precluding fumes and smoke spreading throughout the kitchen.

The invention in all of its details will be fully understood from the following description and claims when the same are read in connection with the drawings, accompanying and forming part of this specification, in which:

Figure 1 is a vertical section showing the arrangement of the canopy constituting the best practical embodiment of our invention, relative to a cooking range. Fig. 2 is a view taken at a right angle to Fig. 1 and showing the canopy in elevation and as partly broken away.

Similar numerals of reference designate corresponding parts in both views of the drawings:

Among other elements our novel canopy comprises a pendent shield 1. This shield, which is preferably of sheet-metal, is fixed to the ceiling 2 of the kitchen and depends therefrom about the proportional distance illustrated. It is preferably, though not necessarily, enameled in order that it may be readily cleared of collected grease at intervals or when occasion demands.

At 3 is a vent duct which may be connected with an uptake or any other suitable outlet (not shown). The said duct 3 is located above the range 4, and in its front wall is provided an induction opening 5, controlled by a sliding door 6 which is designed to be operated by a handle 7, disposed within convenient reach of the chef. We show only one opening 5 and the appurtenances thereof, but it will be understood that in practice a number of openings 5 and controlling devices complementary thereto will be employed.

Hinged to and extending forwardly and upwardly from the lower forward corner

of the duct 3 is the baffle 8 of our improvement. The said baffle when in the position shown in Fig. 1 by full lines, is designed to cause fumes, smoke, etc., to take the tortuous course indicated by arrows in Fig. 1 *en route* from the range to the opening 5, and when in the position shown by dotted lines in Fig. 1, the baffle is adapted to be expeditiously and easily cleaned as is frequently necessary in order to reduce the fire risk.

The baffle 8 is, for the sake of convenience in manipulations, made in three (more or less) sections, and these sections have their meeting ends lapped as indicated by 9 in Fig. 2; the preferred arrangement being to arrange the ends of the inner section above the inner ends of the outer sections. The outer sections are suspended in working position by hangers 10, and hence said outer sections serve to support the inner section in said position. Each of the sections referred to is hinged to the corner of the duct 3. The end sections are apertured to receive the lower portions of the hangers 10, and mounted on the said hangers and disposed below the end sections 8 are wing nuts 12. From this it follows that when the wing nuts 12 are removed, the end sections of the baffle will drop to the pendent position shown by dotted lines in Fig. 1, and the intermediate or inner section of the baffle will follow the end sections to said position, in which all of the sections may be expeditiously and easily cleaned.

In the preferred embodiment of the invention, a continuous angle iron 11 is arranged on the hanger 10, and the several sections of the baffle are clamped by nuts 12 against the said continuous angle iron.

In the practical use of the canopy, it will be manifest that smoke will take approximately the route shown by arrows in passing to the vent 5; and it will also be manifest that the inclined baffle will lead smoke and fumes to the said vent. In the event of fire breaking out, the flames will strike the baffle and spread, and as at that time the vent opening 5 would be closed, the suction would be cut off and the risk of fire damage would be materially lessened.

While we prefer to make the shield 1 of sheet metal, it may be made of tile, plastic material or any other material suitable to its purpose without involving departure from the scope of our invention as claimed.

A curvilinear filler 13, of any appropriate material, is preferably employed in the corner between the shield 1 and the ceiling of the kitchen with a view to facilitating the 5 passage of smoke, fumes, etc., to the opening or openings 5.

The vent duct 3 may be provided in its bottom with clean out doors, but these are 10 common in the art and it is therefore deemed unnecessary to illustrate the same.

We have illustrated and described the preferred arrangement of the baffle 8 relative to the vent duct 3 and the other elements, but we would have it understood that 15 the baffle can be arranged in any other approved manner and can be mounted to swing in any direction without departure from the scope of our claims.

Having described our invention, what we 20 claim and desire to secure by Letters-Patent, is:

1. A canopy for cooking ranges, comprising a pendent shield, a duct positioned above the range and having a vent opening 25 in its forward wall, a baffle extending forwardly and upwardly from the lower portion of the duct and suitably supported in position, a door for controlling the vent opening, and depending means through 30 which the door can be moved.

2. A canopy for cooking ranges, comprising a shield connected with and depending from the ceiling of a kitchen, a duct positioned above the range and having a vent 35 opening in its forward wall, a baffle hinged to and extending forwardly from said duct, hangers connected with the ceiling and detachably connected with the baffle, a door for controlling the vent opening, and depending means through which the door can 40 be operated.

3. A baffle comprising lapped sections arranged to be swung upwardly and downwardly and hinged to a suitable support, 45 and means detachably connected with certain of the sections for supporting all of the sections in working position.

4. A cooking range, a pendent shield ar-

ranged above and in front of the range, a duct positioned above the range and in 50 spaced relation to the shield and having a vent opening in its wall adjacent the shield, and a baffle extending forwardly and upwardly above the range and below the vent opening and to a point adjacent the shield. 55

5. In a canopy, the combination of a duct having a vent opening in its wall, a baffle hinged at a point below said vent opening and extending upwardly and forwardly from said hinge point, and means detachably maintaining the baffle in said position. 60

6. In a canopy, the combination of hinged baffle sections arranged in lapped relation, hangers depending from an overhead support and extending through apertures in 65 the lowermost baffle sections, a bar carried by the hangers and against which the lapped sections bear upwardly, and nuts removably arranged on the hangers and disposed below the lowermost baffle sections. 70

7. A cooking range, a shield arranged above and in front of the range, a duct spaced from the shield and having a vent opening and means for controlling the same, and a baffle arranged to form in combination with the shield a tortuous passage leading from the range to the vent opening. 75

8. A canopy for cooking ranges; comprising a pendent shield, a duct positioned in spaced relation to the shield and having a 80 vent opening in its wall adjacent the shield, a baffle hinged at a point below said vent opening and extending upwardly and forwardly from said hinge point, and means detachably maintaining the baffle in said position. 85

In testimony whereof we have hereunto set our hands in presence of the subscribing witnesses.

JOHN EDWARD GLOEKLER.
ALFRED B. STAHL.
